US00D645049S

(12) **United States Design Patent**
Faranda et al.

(10) **Patent No.:** **US D645,049 S**
(45) **Date of Patent:** **** Sep. 13, 2011**

(54) **COLLAPSIBLE USB CONNECTOR**

(75) Inventors: **Robert Faranda**, Boxborough, MA (US); **Agus Suryana The**, Mesa, AZ (US); **Ross Weems**, Phoenix, AZ (US); **Walter Thornton**, Phoenix, AZ (US)

(73) Assignee: **IGO, Inc.**, Scottsdale, AZ (US)

(**) Term: **14 Years**

(21) Appl. No.: **29/382,226**

(22) Filed: **Dec. 30, 2010**

(51) LOC (9) Cl. **14-02**

(52) U.S. Cl. **D14/480.5**; D13/108

(58) **Field of Classification Search** D14/411, D14/433, 435.1, 436, 480.1–480.7, 484.1, D14/137, 155, 203.1–203.8, 240; D3/201, D3/273; D13/107, 108, 110, 133, 154, 184; 710/300, 301; 439/131, 135–147

(57) **CLAIM**

The ornamental design for the collapsible USB connector, as shown and described.

DESCRIPTION

FIG. 1 is a front perspective view depicting an embodiment of a new design for a collapsible USB connector; FIG. 2 is a front view depicting the embodiment of the new design for the collapsible USB connector of FIG. 1; FIG. 3 is a back view depicting the embodiment of the new design for the collapsible USB connector of FIG. 1; FIG. 4 is a right side view depicting the embodiment of the new design for the collapsible USB connector of FIG. 1; FIG. 5 is a left side view depicting the embodiment of the new design for the collapsible USB connector of FIG. 1; FIG. 6 is a top view depicting the embodiment of the new design for the collapsible USB connector of FIG. 1; FIG. 7 is a bottom view depicting the embodiment of the new design for the collapsible USB connector of FIG. 1; FIG. 8 is a front perspective view depicting another embodiment of a new design for a collapsible USB connector with no claim being made to the keychain opening of the collapsible USB connector, or the front and back side finger grips of the collapsible USB connector; FIG. 9 is a front view depicting the embodiment of the new design for the collapsible USB connector of FIG. 8; FIG. 10 is a back view depicting the embodiment of the new design for the collapsible USB connector of FIG. 8; FIG. 11 is a right side view depicting the embodiment of the new design for the collapsible USB connector of FIG. 8; FIG. 12 is a left side view depicting the embodiment of the new design for the collapsible USB connector of FIG. 8; FIG. 13 is a top view depicting the embodiment of the new design for the collapsible USB connector of FIG. 8; and, FIG. 14 is a bottom view depicting the embodiment of the new design for the collapsible USB connector of FIG. 8. The broken line showings of the keychain opening and the finger grips in FIGS. 8–14 are included for the purpose of illustrating unclaimed portions of the collapsible USB connector and form no part of the claimed design.
